UNITED STATES PATENT OFFICE.

LOUIS C. VANDERLIP, OF ELKHART, INDIANA.

HOOD CLAMP FOR AUTOMOBILES.

Original application filed December 11, 1926. Serial No. 154,055. Divided and this application filed June 24, 1927. Serial No. 201,941.

This invention relates to automobile devices, and especially to hood clamps therefor.

The principal object of the invention is to provide a hood clamp which exerts both a downward and a lateral pressure upon the engine hood, the lateral pressure being effected by non-metallic cam means.

Another object of the invention is to provide a hood clamp which exerts both a downward and a lateral pressure upon the engine hood, the lateral pressure being effected by coacting cam elements, one of which is rubber.

Other objects of the invention are mentioned and described herein.

This application is a division of applicant's application No. 154,055, filed Dec. 11, 1926.

The preferred embodiment of the invention is illustrated in the accompanying drawing wherein, Figure 1 is a side elevation of an engine hood and illustrating the invention applied thereto; Fig. 2 is a front elevation thereof; Fig. 3 illustrates two views of the one piece hold down clamp bracket; Fig. 4 is a section taken on line 4-4 of Fig. 1; and Fig. 5 is a front elevational view thereof.

Similar numerals of reference indicate like parts throughout the several views on the drawing.

Referring to the details of the drawing, the numeral 1 represents a frame section of a motor car to which the hood abutment-element 2 may be rigidly attached interiorly of the hood 3 to limit the inward movement of the latter when it is subject to pressure exerted by a hood clamp, as hereinafter described. The numeral 4 indicates a clamp keeper, preferably made of ductile sheet metal, and rigidly secured to the hood exterior by rivets 5 which may engage the downward extension or body portion 6 of the keeper. A wedge shaped cam element, preferably made of soft rubber and numbered 7, may be secured to the keeper extension 6 adjacent the lower end thereof, as by integral lugs 8 which engage the opposite sides of said cam. An abutment lug 9, preferably integral with the body 6 of the keeper, and projecting laterally therefrom, serves to prevent upward displacement of the cam 7. Preferably, the outer face of the cam element 7 is inclined in respect to the hood wall 3 to effect lateral inward pressure upon the hood when the cam engages a stationary cam, as is hereinafter described.

The hold-down section or unit of the clamp may comprise the hollow cylindrical spring barrel or casing 10 which is apertured and constricted at its lower end 14 to admit the passage of the usual spring rod 11 and within which the usual coil spring 12 is compressed about the rod and seated, respectively, on the rod head 13 and the casing end wall 14. The numeral 15 indicates the usual latch element mounted rigidly on the upper end of the spring casing 10 and which may be provided with the handle 17 and the hook 16 adapted to engage the keeper 4. The lower end of the spring rod 11 may be provided with the hinge eye 18 pivotally mounted upon the hinge pin 19 which has its opposite ends carried in the bracket element 20, the latter being rigidly secured to the frame element 1, as herein-after described, by bolts 21. As illustrated, the clamp bracket 20 is preferably made from a single piece of ductile sheet metal and comprises the base portion 20, the hinge prong sections 22, suitably apertured to carry the hinge pin 19, the lateral wings 23, suitably apertured to take the fastener bolts 21, and the stationary cam section 24 which is adapted to be engaged by the rubber cam 7 and to coact therewith when the hood 3 is drawn downward by the urge of the spring 12 of the hold-down clamp unit.

In a device of this character it is very essential that the means used to prevent rattle of the hood shall exert both a downward pull as well as a lateral thrust inwardly on the hood, and the latter must be sustained and sufficient to prevent outward movement of the hood under all driving conditions. In this device the rubber cam 7, or the element 20, will permit the hold-down clamp to fully draw the hood downward in the proper manner and to the maximum extent on account of their resilient and yieldable character, thereby effecting the desired inward lateral pressure on the hood and also eliminating metallic sounds due to the engagement of the coacting cam elements.

I claim:

1. In an automobile hood clamp, the combination of a hood, a hood abutment within the hood, a spring actuated hold-down clamp positioned exteriorly of the hood and adapted to exert downward pressure upon the hood, and yieldable, non-metallic cam means carried by the hood operative when the hood is depressed by said clamp for projecting the

- hood laterally into engagement with said abutment.
2. In an automobile hood clamp, the combination of a hood, a hood abutment, a spring actuated hold-down clamp adapted to exert downward pressure upon the hood, and yieldable, resilient, nonmetallic cam means carried by the hood operative when the hood is depressed by said clamp for projecting the hood laterally into engagement with said abutment.
3. In an automobile hood clamp, the combination with a hood, of a combined metallic keeper and cam mount rigidly secured to the hood, a yieldable, non-metallic cam element secured to said combined keeper and cam mount, a spring actuated hold-down clamp connected with said keeper and adapted to exert downward pressure upon the hood, and 20 a stationary cam element adapted to coact with said hood cam for projecting the hood laterally.
4. In an automobile hood clamp, the combination with a hood, of a hood abutment, a spring actuated hold-down clamp adapted to exert downward pressure upon the hood, and coacting cam means for projecting the hood laterally against said abutment, said cam means including a metal element and a non-metallic, yieldable element, one of said cam elements being carried by the hood.
5. In an automobile hood clamp, the combination of a hood, a spring actuated hold-down clamp adapted to exert downward pressure upon the hood, bearing means for said hold-down clamp, and coacting cam means for exerting lateral pressure upon said hood, said cam means including a non-metallic element carried by the hood and a stationary element integral with said clamp bearing means.
6. In an automobile hood-clamp, the combination of a hood, a combined metallic keeper and cam mount rigidly secured to the hood exterior, a yieldable, non-metallic cam element carried by said keeper and cam mount and secured thereto by fastening means which is integral with said keeper and cam mount, a spring actuated hold-down clamp connected with said keeper and adapted to exert downward pressure upon the hood, and stationary cam means adapted to coact with said hood cam for exerting lateral pressure upon the hood.
7. In an automobile hood clamp, the combination with a hood, of a hood abutment, a spring actuated hold-down clamp adapted to exert downward pressure upon the hood, and co-acting cam means for projecting the hood laterally against said abutment, said cam means including a metal element and a non-metallic, yieldable element, the latter being carried by the hood.
8. In an automobile hood clamp, the combination with a hood, a hood abutment, and a base frame element, of a spring actuated hold-down clamp adapted to exert downward pressure upon the hood, and co-acting cam means for projecting the hood laterally against said abutment, said cam means including a metal element and a non-metallic, yieldable, element, one of said cam elements being carried by the hood and the other by said base frame element.

In witness whereof I have hereunto affixed my signature this 22nd day of June, 1927.

LOUIS C. VANDERLIP
